UNITED STATES PATENT OFFICE.

ALFRED ERNEST HUDD, OF MELBOURNE, AND GEORGE HARRY WION, OF BRIGHTON,
VICTORIA, AUSTRALIA.

ELECTRICAL POINT-DETECTOR FOR RAILWAYS.

1,343,133.

Specification of Letters Patent.

Patented June 8, 1920.

Application filed June 8, 1917. Serial No. 173,659.

To all whom it may concern:

Be it known that we, ALFRED ERNEST HUDD, a subject of the King of Great Britain and Ireland, etc., residing at Whitehall, 5 Bank Place, Melbourne, in Victoria, Australia, and GEORGE HARRY WION, a citizen of the United States of America, residing at Bellefonte, Union street, Brighton, in Victoria, Australia, have invented certain new 10 and useful Improvements in and Relating to Electrical Point-Detectors for Railways; and we do hereby declare the following to be a full, clear, and exact description of the invention, such as will enable others skilled 15 in the art to which it appertains to make and use the same.

The present invention relates to an electric detection means adapted particularly for application to switch points, and has for 20 an object to provide means of this character for showing when the said points are properly seated or moved into their respective open or closed positions when actuated by any well known manual or automatic switch 25 point throwing mechanism.

Another object of this invention is to provide an electric detection means which is adapted to show when the switch points are not in their required positions as determined by the manual or automatic mechanism 30 when operated, or when the switch points are not returned to their normal determined positions subsequent to automatic actuation by the passage of rolling stock 35 thereover.

The above, and various other objects and advantages of this invention, will be in part described in, and in part understood from, the following detailed description of the 40 present preferred embodiment, the same being illustrated in the accompanying drawings forming a part of this application.

In the accompanying drawings Figure 1 is a plan of our detector box with its cover 45 removed.

Fig. 2 is an elevation on line R—S of Fig. 1.

Fig. 3 is a plan of the plunger bar, (or its extension) and pivoted lever.

50 Fig. 4 is a plan, and Fig. 5 an elevation showing one of the levers used. Fig. 6 is a plan, and Fig. 7 an elevation, showing the commutator, or circuit controller, Fig. 8 is a plan, and Fig. 9 an elevation, showing

crank details. Fig. 10 is a plan of a sliding bar and Fig. 11 a plan of a second sliding bar. Fig. 12 is a plan of the plunger bar but omitting the lever. Fig. 13 is an elevation of part of the detector case with its latch closed, and Fig. 14 another elevation thereof with the latch open.

Fig. 15 is a diagram showing permanent way compound points or slips fitted with our invention.

Fig. 16 is a diagram showing electrical 65 connections.

In various figures some of the parts have been omitted or broken out for clearness of illustration or to save space.

Our detector box or casing (see Figs. 1, 2, 13, and 14) has a lid B having a water proofing gasket 36, and has latch lugs 43 and holding down bolt lugs 38*.

Box A has guides 2, 3, having bases 2¹, 3¹, with upstanding sides 2*, 3* adapted to receive slotted sliding bars C, D, 2**, 3** are bolted cover plates.

The base 21 (Fig. 2) of the detector box is provided with a guide 4 having depending sides 4¹, adapted to receive a slotted 80 sliding plunger bar E (Figs. 1, 2, 3, and 12) and provided with a cover plate 4* secured with bolts.

Base 21 having bearing plates 7¹, carries a shaft 5 axially arranged at the cross intersection of the longitudinal axes of the slotted sliding bars and the slotted plunger bar, shaft 5 being adapted to carry two levers F and G and base plate 23 with its contacts as described. Lever G is shown as mounted to 90 lie within slot 7 in the plunger bar E and is formed with a head d so designed that at one predetermined position of bar E it may occupy recess 6 formed in one side of the long slot 7, and at another predetermined 95 position of bar E recess 8 in the opposite side of slot 7. Alternatively, lever G may be arranged to lie outside the plunger bar E, or clear of slot 7 and the head d (or heads as hereinafter set out) may depend from 100 lever G and occupy a recess or recesses or projection or projections as hereinafter set out. Obviously lever G could be constructed with a head (as d) at each end and recesses in slot 7 to co-act therewith.

The lever F is located within slots 15 and 16 formed in one, two, or more sliding bars C, D, said bars moving in a plane and direc-

tion other than in the plunger bar E, and being connectible by rods and links to the switch points. Lever F is provided with two heads e , e^1 designed to occupy at predetermined positions of bars C, D recesses 11, 12, and 13, 14, formed in opposite sides of the long slots 15, 16, in bars C, D; and at other predetermined positions similar recesses 11¹, 12¹, and 13¹, 14¹, in the opposite sides of the said slots. The said construction deals with a slotted bar or bars embracing lever F, but the recesses may be formed in the outside edge or edges of said bar or bars.

15 In the latter case only one head e or e^1 of lever F would engage a recess in one bar, or coacting recesses in two or more bars. Obviously projections may be employed instead of recesses. Obviously lever F could be made with only one head e or e^1 , the recesses in slots 15 and 16 being arranged to coact therewith.

The bar C overlies bar D, both being movable independently, and both being provided with bolts c , c^1 the latter for connecting the said bars to the switch points through intermediate bars or links as is well understood.

Free to oscillate on (or integral with) shaft 30 5 is an oscillating base plate 23 fitted with an insulated contact carrier plate 24 carrying electrical contacts or segments f , f^1 , g , g^1 , and h , h^1 the whole forming a circuit controller or commutator; the contacts being disposed to contact with resilient or spring fingers i , j , k , l , m , n , o , and p , mounted on blocks 34, 34¹ secured to the base 21 by screws as shown, and with terminals q , r , s , t , u , v , w , and x , connected with a source of electrical energy by cables or wires led in through sockets or openings 24¹.

Instead of flat plates, as 23 and 24, we may employ curved plates, rotatable by any suitable intermediate operating mechanism. 40 The oscillating plate 23 may be provided with balls 721 rolling on a path 73 (Fig. 7). Beneath the contact fingers i to p , are keeper plates 72 which regulate the pressure of these fingers on contacts f , f^1 , g , g^1 and h , h^1 .

Lever F is connected to the plate 23 by dowels or screws 5¹ (Figs. 4 and 5) and the lever G to said base plate by dowels or screws 6¹, these three parts constituting a structure oscillating positively as one solid unit, the oscillating being limited by stops 5², 6², (Fig. 1).

Lever G is located within slot 7 of plunger bar E, the head d entering recess 6 or 60 recess 8 according to the position the bar occupies in the guide 4. As the head d of lever G enters say recess 6 the circuit controller or commutator moves into the left hand position as in Fig. 1; when moved out of recess 6 by the operation of the plunger

bar E, the head d ,—entering that portion of the slot lying between the two recesses,—carries the commutator into (and holds it in) the central or neutral position as in Fig. 6. Finally as it enters the recess 8, the 70 commutator is moved into the right hand position, as will be well understood. The commutator is thus arranged to occupy predetermined positions controlling the flow, and the direction of flow of electric energy. 75

As the heads e , e^1 of lever F enter say recesses 11¹, 12¹, 13¹, 14¹ the circuit controller or commutator occupies the left hand position as in Fig. 1, when they are moved out of said recesses 11¹, 12¹, 13¹, 14¹ by the 80 operation of the bars C, D the lever F occupies that position in which its longitudinal axis lies parallel with the longitudinal axes of bars C, D and carries the commutator into (and holds it in) the central or neutral 85 position as in Fig. 6.

Finally when the movement of bars C, D is completed the heads e , e^1 enter the recesses 11, 12, 13, 14 the commutator is moved over into the right hand position, as will be 90 well understood.

One or more of such slotted bars may be employed as desired or according to the number of point blades our apparatus is desired to operate with or detect.

The base 21 of casing A carries two vertical studs 22, 22¹. Free to oscillate on stud 22 is a lever or crank 25 which carries a roller 26 mounted on a pillar arranged to engage with the face y^1 of a striker y carried by and secured to bar C (only one striker is required and may be secured to any of the bars as desired but not attached to more than one bar)—the corners y^2 , y^3 being cut away to permit of easy contact of 100 striker y with the rollers 26 and 26¹. This lever or crank also carries a standard 27 having a forked head 28 to receive the looped end of a wire 29 connected to a flanged coil spring holder 30, within which 105 one end of a coil spring 31 is seated, the other end of the coil spring being seated in a similar holder 32 held by a wire 33 looped over a pillar 34 on the oscillating base plate 23, (Figs. 1 and 6).

Similarly a lever or crank, spring and attachment, are provided on the other side of the oscillating base plate 23, the similar parts being numbered 22² and consecutively from 25¹ to 33¹. The function of these 110 springs is to impel the circuit controller to assume either of two extreme positions.

Seats 35 (Fig. 6) are provided on which the loops of the wire embracing pillar 34 rest. One or other of these coil springs acts 115 to pull over the oscillating base plate 23 with its contacts f to h^1 , into either its extreme right or extreme left position according as the mechanisms are operated.

In Fig. 1 it will be seen that the left hand 120

lever 25 occupies a position unlike that of the right hand lever 25¹; the difference also applies to the rollers 26 and 26¹. This is owing to the movements of the bars C and D to the left carrying the bevel surface y^2 into contact with the roller 26, forcing the lever or crank 25 to pivot about the stud 22, and compressing the spring 31 which is held thus by the surface y^1 of the plate y until 10 through the continued forward movement of bars C and D the recesses 11¹, 12¹ and 13¹, 14¹, occupy a position to admit of the heads e, e¹ engaging with the same; and recess 6 of slot 7 in bar E also occupies a 15 position to admit of the head d of lever G engaging with the same, when the spring 31 will impel the controller to its extreme left position—as in Fig. 1.

When the bars C and D are moved in an 20 opposite direction, and roller 26 is released from surfaces y^1 y^2 , these parts 25, 26, 27, 28 assume the position corresponding to that which parts 25¹, 26¹, 27¹, 28¹ are shown as occupying in Fig. 1. If the movement of 25 bars C and D be continued the surface y^3 will contact with roller 26¹ and with the same results in respect to spring 31¹, and the circuit controller will be impelled to the extreme right hand position, provided all 30 bars C, D, E, are in their proper positions.

If any bar C, D, or E fail to complete its travel so as to occupy the position described the controller will be held in a central or neutral position against the pressure of 35 spring 31 or 31¹.

To secure cover B to case A hinge lugs Z, Z having holes z³, z³ are provided to receive pins projecting from lugs on the cover. On the opposite side of lid B are bolt lugs 40 37 between which is pivoted an L shaped link 38 in which is a hole 39 for the hasp of a padlock. Pivotally attached to link 38 is an L shaped lever 40 having a lip or lips 41 on its short arm and a slot 42 through 45 which the short arm of link 38 protrudes leaving hole 39 clear to receive the padlock hasp. The latch lugs 43 on case A have a depending lip or claw 49 with which the projection or projections 41 engage as in 50 Fig. 13, when lever 40 is in the position shown.

For the purpose of describing the operation of our invention we assume the parts in Fig. 1 occupy their normal position when 55 the head d of lever G occupies the recess 6 of slot 7 of plunger bar E; and the heads e, e¹ of lever F respectively occupy the recesses 14¹, 11¹ in bar C and 13¹, 12¹ in bar D, and the contact plate 24 occupying the 60 position in Fig. 1 over against stop 5*. Conversely the parts occupy their reverse positions when the head d of lever G occupies recess 8 of slot 7 of plunger bar E, and the heads e, e¹ of lever F respectively occupy 65 the recesses 12, 13 in bar C, and 11, 14 in bar

D, and the contact plate 24 occupies a position to the right over against stop 6.

The recesses 14¹, 11¹, in bar C—and 13¹, 12¹, in bar D—register with heads e, e¹ of lever F, and recess 6 in bar E registers with 70 head d of lever G when the points are, say, normal; and the recesses 12, 13, in bar C—and 11, 14 in bar D—register with heads e, e¹ of lever F and recess 8 in bar E registers with head d of lever G, when the points are, 75 say reversed.

The said recesses may be so disposed and made of such length as to act upon the levers F and G so that when either or all of the bars C, D and E are moved from either their 80 normal or reverse positions by any predetermined amount the said arms, together with the contact plate 24, will be positively forced toward the central position against the pressure of the springs 31 or 31¹.

The recesses above referred to may be formed of any desired length so that any predetermined movements of bar E, bar C, or bar D will force the contact plate 24 to the central position thereby making or 90 breaking circuits, as may be arranged according to the disposition of contact springs as i, j, k, l, m, n, o, and p in relation to the contact segments as f, f¹, g, g¹, h, h¹, as may be mounted upon the contact 95 plate 24.

An incorrect movement of the plunger bar E or the switch points acting through the bar C, D, will always positively move the oscillating base plate 23 (with contact plate 100 24) toward its central position; and thus we obtain the required detection of the condition of a pair of points and its lock.

When the plunger bar E pushes against the head d of lever G it forces it out of 105 recess 6 or 8 against the pressure of spring 31 or 31¹; the lever G rides hard on the edges of slot 7 until the spring pressure is released, by movement of bars C, D, connected to the switch points.

The foregoing description refers to a detector as applied to a single pair of points and as would be constructed for left hand location.

Fig. 15 shows an application of our invention to compound points or slips. Two each of bars as C and D with recesses as shown are used, but with the difference that one end of each of the two bars C which lie between the two bars D, is curved, for instance 120 as shown in Fig. 15. Striker y is attached as before to one bar only, preferably the uppermost and the lever F must be deep enough to engage all the said bars. The curved ends of bars C allow upper and lower 125 pivot bolts 66 one in each bar to be clear of pivot bolts 67 on bars D.

To the bars C are pivoted by bolts 66 two bars or rods 50, 53. Rod 50 is pivoted to the top of bar C, and rod 53 is pivoted to 130

the bottom of bar C. Rod 50 is pivotally connected to an extension piece 52 attached to switch point 51, which closes on to a rail 70. Rod 53 is pivoted to an extension piece 54 attached to switch point 55 which closes on rail 71.

Pivoted to the bars D by bolts 67, are two bars or rods 65 and 66. Rod 65 is pivoted to the top of bar D and rod 66 is pivoted to the bottom of bar D. Rod 65 is pivotally connected to the extension piece 59 attached to switch point 61 which closes on to the rail 70^a. Rod 66 is pivotally connected to an extension piece 64 attached to switch 15 point 67 which closes on to the rail 71^a.

The extension 52 carries a bracket or lug 56, pivotally connected to which is a bar 57 pivotally connected to a bracket or lug 58, carried by an extension piece 59 attached to 20 switch point 61, which closes on to the rail 70^a, thus linking together the blades 51 and 61, and compelling both to move in unison.

The extension 54 carries a bracket or lug 60, pivotally connected to which is a bar 62 25 pivotally connected to a bracket or lug 63 carried by the extension piece 64 attached to the switch point 67 which closes on to the rail 71^a, thus linking the switch points 55 and 67 together and compelling both to move 30 in unison. Bars 57 and 62 are linked up to any suitable locking mechanism (not illustrated) operated by plunger rod E, an extension of which passes through the detector box and contains slot 7.

35 The motion of the points will simultaneously operate the bars C and D and the parts in the case A, including the oscillating base plate 23 with electrical contact springs carried thereby, thus revealing the positions of 40 the said points whether normal, reverse, or intermediate (that is any position in which the switch points are not "home" and the roads properly and securely "made").

Fig. 16 illustrates an application of our 45 invention in which two complete detector boxes J and K are connected to two separate sets of points operated by a common lever in the signal box, but in detector box K the segments g and h¹ shown in the box J are 50 omitted.

It will be understood that the parts diagrammatized in Fig. 16 are linked up as usual to the parts with which they work and with semaphores or other signaling means.

55 The class of energy may be either alternating or direct current, and of whatever voltage is desired.

H is a polarized or three position relay having terminals 44, 45; terminal 44 is connected by wire W⁵ to the contact spring n of detector box K, and terminal 45 through wire W⁶ to spring o of same detector. The spring n of box K is also connected through wire W¹² to j; o to k of box K through wire 60 W¹¹; p of K to o of box J by wire W³, and m

of box K to n of box J by wire W⁴; l of box K to k of box J by wire W², i of box K to j of box J by wire W¹, p of box J to i of box J by wire W¹⁰, and m of box J to l of box J by wire W⁹. 70

Spring l of box J is also connected by wire W⁸ to one terminal N (say negative) of a source of electrical energy; and i of box J by wire W⁷ to the other terminal P (say positive) of the said source of energy. 75

The contact carrier of box J is provided with contacts f, f¹; g, g¹; h, h¹ and the contact plate carrier of box K with contacts f, f¹, g¹, and h.

When the points are in say, the normal 80 position as illustrated the connections will be as follows:—

Positive energy will flow from terminal P over wire W⁷ to spring i of box J through contact segment f¹ to j of box J; thence 85 through wire W¹ to i of box K, through segment f¹ to j of box K, and thence over wire W¹² and wire W⁵ to 44 of relay H, through a coil or winding 46 to 45 of relay H, over wire W⁶ and wire W¹¹ to k of box K, 90 through segment f to l of box K, thence over wire W² to k of box J through segment f to spring l of box J thence over wire W⁸ to terminal N. Wires W³ and W⁴ connected to o and n of box J are short circuited through segment h¹. 95 The flow of current through relay H causes the latter to operate so as to close a set of electrical contacts corresponding to the assumed normal position of the rail points. 100

When the points are in the reverse position to the above the connections will be as follows:—

Positive energy will flow from terminal P over wire W⁷ and W¹⁰ to contact p of box J, 105 thence through segment f¹ to o of box J, over wire W³ to p of box K, through segment f¹ to o of box K, thence over wire W⁶ to terminal 45 of relay H, through a coil or winding 46 of relay H to 44, thence over 110 wire W⁵ to n of box K, through segment f to m of box K, via wire W⁴ to n of box J, through segment f to m of box J, thence over wire W⁹ and wire W⁸ to terminal N.

Wires W¹ and W² connected to j and k 115 of box J are short circuited through segment g of box J.

The flow of current through relay H causes the latter to operate so as to close a set of electrical contacts corresponding to 120 the assumed reverse position of the rail points.

It will be seen that when the parts were in normal position the current flowed through the coil 46 of relay H in the direction from 44 to 45, and that in the reverse position the current flowed through the coil 46 from 45 to 44. 125

Signals governing train movements over points to which box J and box K are at- 130

tached may have their electrical control circuits taken through either normal or reverse contacts in relay H as may be required, thus detecting that said points are 5 in their proper position for the desired train movement.

If any condition such as previously outlined causes the base plate 23 of box K with its contact plate 24 to occupy a central position 10 all energy will be disconnected from contacts n, o of box K and k, j of box K; and further, wires W⁵ and W⁶ will be short circuited between n and o through segment k of box K, and between j and k of box K 15 through segment g¹ of K, thus leaving the coil or winding 46 of relay H disconnected from energy as well as being short circuited.

Assuming another condition in which box K is normal and box J occupies the central 20 position:—In this position all energy is disconnected from contacts k and j of box J, and wires W¹ and W² are short circuited between j and k through segment g¹ of box J, thus again leaving the coil 46 or relay H 25 disconnected from energy and short circuited.

Assuming another condition in which box K is reversed and box J occupies the central position:—Then all energy is disconnected 30 from the contacts n and o of box J, and wires W³ and W⁴ are short circuited between o and n through segment h of box J, thus again leaving the coil 46 of relay H disconnected from energy and short circuited. 35

Assuming another condition in which box K is normal; and box J is reversed:—Then all energy is disconnected from contacts j and k of box J, and wires W¹ and W² are 40 short circuited between j and k through segment g of box J, thus again leaving the coil 46 disconnected from energy and short circuited.

Assuming another condition in which box K is reversed and box J normal:—Then all 45 energy is disconnected from contacts n and o of box J, and wires W³ and W⁴ are short circuited between o and n through segment h¹ of box J, thus again leaving the coil 46 50 of relay H disconnected from energy and short circuited.

In the foregoing we have described and illustrated mechanism or mechanisms to give effect to our invention, but we do not limit 55 ourselves to parts as shown in the drawings but may adopt modifications without departing from our invention.

What we claim as new and desire Letters Patent for is:—

60 1. Detector apparatus for switch points including intersecting bars, levers to co-act

with the bars, and a controller to be moved or oscillated about the point of intersection of the bars, as and for the purposes set forth.

2. A detector apparatus for switch points 65 including bars movable with the switch points, levers connecting with the bars, and a controller movable about the point of intersection of the bars, substantially as described.

3. Detector apparatus for switch points 70 including bars, levers moved by said bars, and a controller moved by said levers about the point of intersection of the bars, substantially as described.

4. Detector apparatus for switch points 75 including intersecting bars having slots therein and recesses in the slots, levers occupying the slots in said bars and having heads to engage in said recesses, and a controller connected to said levers, substantially as described.

5. Detector apparatus for switch points 80 including intersecting bars having slots therein and recesses in the slots, levers occupying the slots in said bars and having heads to engage in said recesses, and a controller movable about the point of intersection of the bars and connected to said levers, substantially as described.

6. In a detector apparatus for switch 85 points and their locking mechanism, the combination of movable bars connected to said switch points and to the locking mechanism, said bars having slots therein and recesses in the slots, levers in the slots having heads engageable in the recesses, and a controller rigidly connected to said levers and rocking with the levers when said bars are moved, substantially as described.

7. In a detector apparatus for switch 90 points and their locking mechanism, the combination of bars movable with the switch points and having slots therein and recesses in the slots, a plunger bar movable with the locking mechanism and having a slot therein and recesses in the slot, a controller, and a pair of levers rigidly connected to said controller, one of said levers being fitted in the slots in said first mentioned bars, the other lever being arranged in the slot in said plunger bar, said levers having heads engageable in the recesses in said bars, the levers being rocked by the movement of said bars, substantially as described.

In witness whereof we have hereunto set our hands in presence of two witnesses.
